UNITED STATES PATENT OFFICE.

LOUIS GEORGES DERAIN, OF BOULOGNE-SUR-SEINE, NEAR PARIS, FRANCE.

EXTRUSION-PRESS.

1,037,213.

Specification of Letters Patent.

Patented Sept. 3, 1912.

Application filed February 14, 1911. Serial No. 608,542.

To all whom it may concern:

Be it known that I, LOUIS GEORGES DERAIN, of Boulogne-sur-Seine, near Paris, France, engineer, have invented certain new and useful Improvements in Extrusion-Presses, of which the following is a specification.

This invention relates to extrusion presses of the kind in which an ingot raised to a temperature varying with the metal under treatment, but properly determined according to the nature of the metal, is placed in a cylindrical chamber called a container, and is then forced by pressure through an extrusion die located at the end of the container. The section of the opening of this die corresponds to the profile to be produced. Machines as at present employed for this method of manufacture cannot force the whole of the ingot through the die, as the plunger for forcing the metal out of the container and through the die cannot be allowed to come right up against the die without risk of breakages. Consequently, when the tube, bar or the like is drawn or extruded, it remains attached at one end to a tail piece or sprue located at the entrance to the die. In order to release the tube, bar or other article, the die has to be shifted to bring it out of the machine, and the sprue has to be cut off in front of the die, an operation that necessitates shifting of the die and cutting off the sprue hot. During these operations the machine is doing no work, and consequently the output is greatly reduced.

The present invention dispenses with the operation of cutting off the sprue hot in the press itself. For this purpose I employ a divided die provided with means whereby the members thereof are adapted to be brought together for the extrusion operation and to be moved apart to permit of the removal of the article.

The die will generally be made in two or more parts each of which may be mounted on a plunger, piston, slide or the like. At the end of the extrusion operation the two portions of the die are moved apart to allow the tube or article to be withdrawn with the sprue attached. The sprue may then be sawed or cut off cold in a separate shop. The manufacture can thus proceed without interruption.

In a form of apparatus according to the invention the die is divided longitudinally into two or more parts and is arranged in combination with an ingot container adapted to be moved longitudinally toward and away from the die, and means are provided for moving the portions of the die apart after suitable retraction of the container, so as to enable the article produced to be withdrawn. The container is preferably arranged and operated so as to grip or bind upon the die when advanced, and keep the same firmly together for the extrusion operation.

The pistons, plungers, slides or like devices for carrying the parts of the die may be arranged to be moved together and apart by hydraulic or other mechanism, so as to close and open the die at the required times. This operation of the die-carrying devices may be imparted to them by means of the reciprocating movement of the container, through the medium of levers or other suitable devices, so arranged and combined that when the container is retracted the die is opened, and that when the container advances the die is closed. The container is preferably so arranged and operated that after the die parts are brought together it envelops and binds or holds them together for the extrusion operation.

According to a further part of the invention a resilient connection is provided between the die-carrying devices and their operating levers or members, this connection being adapted to come into action when the container comes upon the parts of the die in enveloping or clamping the same.

The invention comprises further improvements in details, which will appear from the description and claiming clauses.

The accompanying drawings show by way of example a form of the machine constructed to embody the invention.

Figures 1, 2 and 3 represent the machine in longitudinal elevation, plan and end view respectively. Figs. 4, 5 and 6 are detail longitudinal sections on a larger scale taken on A A Fig. 2 and B B Fig. 3 and showing respectively the front, middle and rear portions of the machine. Figs. 7, 8 and 9 are respectively sections on C D E F, G G and H H of Fig. 4. Fig. 10 is a detail section of the die. Fig. 11 is a detail sec-

tion through the container and die showing the construction and operation of a special detachable mandrel for tube extrusion. Fig. 12 is a similar view of a modified form of such mandrel.

5 The press comprises two vertical heads on ends 1, 2 united by two horizontal stay frames, 3, 3 formed with collars embracing the cylindrical extremities of the heads 1, 2. 10 The head 1 is cylindrical and forms a pivot for the cylinder 4, which is constructed for this purpose with half collars or bearings to which are bolted the corresponding members 5, 5 Fig. 6. By this means the cylinder 15 can be turned around its pivot as required, which is a matter of convenience in erecting fitting or repairing the press. At the other end the cylinder 4 is fixed in position adjustably with relation to the stay frames 3 20 by bolts 6, Fig. 1. The head 7 of the piston of the press is fitted in a dovetail seating 8^a 8^a in a carriage or slide 8 (Figs. 1 and 5) guided by the stay frames 3. This method of fitting the piston in the carriage 25 facilitates erection and dismantling. In the slide 8 is fitted a second slide 9 adapted to be traversed across the machine and carrying the plunger 10.

The head 11 of the plunger 10 is detachably connected to the plunger for example by a right and left handed screw 10^a as shown, and can be readily replaced according to the work required. For the production of profile bars of solid section the head 35 11 will usually be solid. For the production of tubular articles it will generally be constructed hollow as shown for example, in Figs. 4, 11 and 12 so as to provide a cylindrical, or equivalent seating for the head 12 of a solid mandrel 13 corresponding exactly with the interior of the tube to be obtained.

The ingots employed for the production of tubes are as known formed with a longitudinal hole to give passage to the mandrel which is forced forward by the plunger through the die with the metal of the ingot. In the construction shown in Figs. 4 and 11, the head 12 of the mandrel 13 has a shoulder 50 130 at front and fits with a little friction in a socket 131 at the forward end 11 of the plunger, the head 12 and the forward end of the plunger being flush with each other at front and occupying the full width of the 55 opening 132 in the container, and the mandrel being coaxial with the opening and with the die 20, 21. Thus while the mandrel will move forward with the plunger in the extrusion operation, the plunger can 60 recede independently of the mandrel if this should jam in the extruded tube. At the same time the metal of the ingot 133 cannot penetrate back behind the mandrel if this should tend to be drawn forward by the 65 more rapid flow of the metal at the front

through the die; on the contrary there is always opposed to the back of the metal of the ingot during extrusion a shoulder or wall occupying the full width of the clearance between the mandrel and the interior of the opening in the container. The same result can be attained by fitting the end of the mandrel with slight friction on the forward end of the plunger instead of in a recess therein. Such an arrangement is 70 shown in Fig. 12. Here the head 12^a of the mandrel is seated on a tenon 131^a of the detachable end 11 of the plunger, the front face of the mandrel head 12^a occupying the whole width of clearance between the mandrel and the container.

75 In the production of thick or heavy tubes the mandrel may be tubular, in order to make it lighter and to enable it to cool more rapidly. The mandrel lies accurately in the axis of the die 20, 21 and insures equal or symmetrical distribution of the thicknesses 80 of the metal.

85 When the slide 8 is moved back by the ordinary retractor cylinders 14, 15 (Figs. 1 and 2) after the extrusion of the ingot, the plunger can recede independently of the mandrel. If the mandrel should jam very tightly in the tube produced, it can be left 90 in and be removed with the tube from the press. Another mandrel can be set in the plunger for the next operation. During this second operation the first mandrel is withdrawn from the drawn article outside the press and can be used for a third operation, 95 and so on.

100 16 is a dowel on the head on the mandrel and fitting in the head 11 of the plunger, this allows of setting the mandrel accurately with relation to the die in cases where the interior profile to be produced is not circular.

105 The carriage 9 can be slid transversely by means of a hand wheel 17 (Fig. 1) when it is desired to uncover the mouth of the container or ingot chamber and the traversing motion also enables the plunger and mandrel to be readily centered relatively to the divided die. A stop is provided to insure that in the return movement the carriage 9 110 and plunger 10 shall come properly to axial position. The forward head or end 2 is bored for its full height and forms a cylinder in which work two pistons or plungers 18, 19 each carrying one portion 20, 21 of a 115 special two-part die (Figs. 4 and 10). These two parts 20, 21 bear against the halves 22, 23 of a cylindrical bolster.

120 24, 25 are half rings fixed to the halves of the bolster and serving to center and support the corresponding parts of the die. The halves 22, 23 of the bolster are secured to the plungers 18, 19 by means of half collars 26, 27 and bolts 28; these half collars 125 likewise serve to prevent the parts of the 130

die from becoming detached from the half rings 24, 25. The halves of the bolster themselves bear against semi-cylindrical thrust blocks 29, 30 centered and held in the 5 plungers 18, 19 by dowels 31.

The construction of the die in two parts also allows of rapidly changing the die. For this purpose it is only necessary to move the plunger 18, 19 apart and then 10 after loosening the bolts 28, the half dies can be turned half around to release them from their seats, whereupon they can be removed from the machine. The operation of the plungers 18, 19 may be independent and 15 can be effected by any suitable means or source of power. In the example shown these plungers are operated by hydraulic power through the medium of the slide 37 hereinafter described and which actuates 20 the container 34 in which the ingot to be operated upon is placed. This container is constructed in the known way of three cylinders 32, 33, 34 fitted together so as to form a block. According to the invention this 25 container fits and is secured by a nut 35 in conical collar or holder 36 mounted by means of trunnions on a C-shaped slide 37 (Fig. 9) guided by the stay frames 3, 3 similarly to the slide 8. The container is 30 kept in its axial position by two strong pins 39, 40 Fig. 1. When these have been taken out, the container can be turned on its pivot into any position which may be desired, for the purpose of dismounting it or for inserting 35 the ingot or for particular operations of the press. For dismounting the container, the pins 39, 40 are removed, the collar 36 is turned around 90° and the nut 35 is unscrewed. Owing to the taper of the collar 40 36 the container can be readily removed from the collar.

The slide 37 is adapted to move longitudinally between the stay frames 3 under the action of a hydraulic cylinder 38 and 45 its movements are imparted to two bent arms 41, 42 (Fig. 4) attached to slide and passing through the head 2 of the press and the pistons 18, 19. These arms act as cams upon rollers 43, 44, 45, 46 mounted on spin- 50 dles fixed in the plungers 18, 19 which are thereby caused to move vertically. When the slide 37 moves the container 34 away from the end 2, the arms 41, 42 act on the rollers 43, 44 and move the pistons apart, 55 thus separating the parts 20, 21 of the die. In the reverse movement, when the slide 37 returns the container 34 against the end 2, the arms 41, 42 act on the rollers 45, 46 and move the two plungers inward so as to bring 60 the parts of the die together, which latter takes place before the container comes upon the conical bearing surface of the die.

A resilient connection is provided between the plungers 18, 19 and the arms 41, 42 by means of the bearings 47, 48 traction

or return rods 49, 50 and springs 52 fitted in boxes 51 (see Fig. 7). When the parts 20, 21 of the die come together the plungers 18, 19 are therefore in resilient relation with the arms 41, 42. This resilient mounting 70 allows the conical bearing face of the die to become accurately seated in the recess provided for this purpose in the container, and compels the latter to bind upon and brace the parts 20, 21 of the die and hold 75 them powerfully together during the extrusion operation, preventing the compressed metal from forcing the die parts away from each other or from penetrating between the piston and the portions of the die. Perfect 80 contact between the bearing faces of the die parts and their seat in the container is also secured. It will be seen that this resiliency of the mounting of the plungers 18, 19 only comes into play when the container 85 comes upon the parts of the die.

The slide 37 may be coupled directly to the slide 8 by rods 53 screwing into lugs 54 and secured by nuts. It can then be drawn back by means of the retractor pistons 14, 90 15 when it is desired to obtain access to or remove the pistons 18, 19. In order to do this, the handwheel 55 is first operated to uncouple the carriage 37 from the rod of the hydraulic cylinder 38. The handwheel 95 56 is then operated to release the spring detent 57 and to allow the same to catch and hold the piston 18 suspended. Then the slide 37 is drawn back and the plungers 18, 19 can now be readily removed from 100 their cylinder.

Instead of hydraulic pressure I may employ other fluid pressure or any other power for operating the plunger, container and die actuating members, or any of these parts 105 as may be desired.

What I claim and desire to secure by Letters Patent is:—

1. In an extrusion press for the manufacture of tubes, bars, rods and the like, a 110 die divided into parts, in combination with a container, said container and die being relatively movable, whereby they may be brought together and apart, and means for moving the members of the die apart after 115 the separation of the die and container, whereby the extruded article can be released.

2. In an extrusion press for the manufacture of tubes, bars, rods and the like, a die 120 divided into parts, in combination with a container, means for moving the container toward and away from the die and means for moving the members of the die apart after retraction of the container, whereby 125 the extruded article can be released.

3. In an extrusion press for the manufacture of tubes, bars, rods and the like, a die divided longitudinally into parts, in combination with a container adapted to grip and 130

bind the die when moved toward the same, means for moving the container toward and away from the die, and means for moving the members of the die together for the extrusion operation and for moving them apart after the retraction of the container, substantially as described.

4. In an extrusion press for the manufacture of tubes, bars, rods and the like, a die divided into parts, members connected to said parts respectively, and means for operating said members to move the die parts together and apart, substantially as and for the purpose described.

5. In an extrusion press for the manufacture of tubes, bars, rods and the like, a die divided into parts, die-operating members connected to said die parts respectively and adapted to move the same together and apart, a sliding container, means for moving said container toward and away from the die and means for imparting the motion of the container to said die operating members, whereby the die parts are brought together in the motion of the container toward the same and are moved apart in the reverse motion of the container.

6. In an extrusion press for the manufacture of tubes, bars, rods and the like, a die divided longitudinally into parts, die operating members connected to said die parts respectively and adapted to move the same together and apart, a sliding container, adapted to grip and bind the die when moved up to the same, means for moving said container toward and away from the die, and means for imparting the motion of the container to said die operating members, whereby the die parts are brought together in the motion of the container toward the same and are moved apart in the reverse motion of the container.

7. In an extrusion press for the manufacture of tubes, bars, rods and the like, a die divided into parts, sliding members connected to said die parts respectively, and means for operating said sliding members to move the die parts together and apart, substantially as and for the purposes described.

8. In an extrusion press for the manufacture of tubes, bars, rods and the like, a die divided longitudinally into two parts, plungers connected to said die parts respectively, a sliding container, means for moving said container toward and away from the die, cam bars in connection with said container, and rollers in connection with said plungers and coacting with said cam bars, whereby the die parts are brought together in the movement of the container toward the same and are moved apart in the reverse motion of the container, substantially as described.

9. In an extrusion press for the manufac-

ture of tubes, bars, rods and the like, a die divided longitudinally into two parts, plungers connected to said die parts respectively, a sliding container adapted to grip and bind on the die when moved up to the same, means for moving said container toward and away from the die, cam bars in connection with said container, and rollers in connection with said plungers and coacting with said cam bars, whereby the die parts are brought together in the movement of the container toward the same and are moved apart in the reverse motion of the container, substantially as described.

10. In an extrusion press for the manufacture of tubes, bars, rods and the like, a die divided into parts, a sliding container adapted to grip and bind the die when moved up to same, power apparatus for moving said container toward and away from the die, and for moving the die parts together for the extrusion operation and apart after retraction of the container.

11. In an extrusion press for the manufacture of tubes, bars, rods and the like, a die divided into parts, die operating members connected to said parts respectively, a sliding conveyer adapted to grip and bind the die when moved up to same, power apparatus for moving said container toward and away from the die and means for imparting the motion of said container to said die operating members, said means being adapted to move the die parts together before the end of the forward motion of the container and to move them apart when the container has receded from the die.

12. In an extrusion press for the manufacture of tubes, bars, rods and the like, a die divided longitudinally into parts, die-operating plungers connected to said parts respectively, a reciprocating container adapted to grip and bind the die, at the end of its forward stroke, a carriage for said conveyer, a hydraulic cylinder and piston for reciprocating said carriage, levers operated by the reciprocation of said carriage and adapted in the forward stroke thereof to move the die operating plungers to close the die parts together before the end of said forward stroke, and to move the plungers to bring the die parts apart in the backward stroke of the container carriage, substantially as described.

13. In an extrusion press for the manufacture of tubes, bars, rods and the like, a die divided into parts, and having a tapered bearing face, in combination with die-operating members connected to said parts respectively, a reciprocating container adapted to grip and bind on the tapered face of the die at the end of its forward stroke, power operated means for reciprocating the container, devices connected to said container and adapted to impart the motion

thereof to the die operating members whereby to close the die parts in the forward stroke of the container, and a resilient connection between said devices and the die operating members for the purpose specified.

5 14. In an extrusion press for the manufacture of tubes, bars, rods and the like, a die divided longitudinally into parts and having a tapered bearing face, in combination with

10 die operating plungers connected to said parts respectively, a reciprocating container adapted to grip and bind on the tapered face of the die at the end of its forward stroke, power operated means for reciprocating

15 the container, levers connected to said container and adapted to impart the motion thereof to said plungers to close the die parts in the forward stroke of the container and to open them in its return stroke, and

20 a resilient connection comprising traction rods and springs between said levers and said plungers for the purpose specified.

15 15. In an extrusion press for the manufacture of tubular articles, a divided die and means for moving the die parts together for the extrusion and apart to release the extruded article, in combination with a container, an extrusion plunger and a mandrel in independent but frictional connection with said plunger, substantially as described.

30 16. In an extrusion press for the manufacture of tubular articles, a divided die and means for moving the die parts together for the extrusion and apart to release the extruded article, in combination with a container, an extrusion plunger, a detachable end for said plunger and adapted for independent but frictional engagement with a mandrel, and a mandrel adapted for independent frictional engagement with said detachable end.

40 17. In an extrusion press for the manufacture of tubular articles, a divided die and means for moving the die parts together for the extrusion and apart to release the extruded article, in combination with a container, an extrusion plunger adapted for independent but frictional engagement with a mandrel, a mandrel adapted for independent engagement with said plunger and to leave a clearance between itself and the interior of the container in the extrusion, and a body at the rear of the mandrel, adapted 50 to fill the rear of the clearance between the mandrel and the container, and to prevent back flow of metal when the mandrel is drawn forward by the metal under extrusion.

55 60 18. In an extrusion press for the manufacture of tubular articles, a divided die and means for moving the die parts together for the extrusion and apart to release the extruded article, in combination with a container, an extrusion plunger pro-

vided with a seat for a head on the mandrel, a mandrel adapted to leave a clearance between itself and the interior of the container in the extrusion and having a head adapted to be fitted independently but with 70 friction to the end of the plunger, and to present a body at the rear of said clearance for preventing back flow of metal when the mandrel is drawn forward by the metal under extrusion.

75 19. In an extrusion press for the manufacture of tubes, bars, rods and the like, the combination of a divided die, means for moving the die parts together for the extrusion and apart to release the extruded 80 article, a container, an extrusion plunger, and a fluid pressure cylinder and piston for operating said plunger, said cylinder being pivotally mounted in the press substantially as and for the purposes specified.

85 20. In an extrusion press for the manufacture of tubes, bars, rods and the like, the combination of a divided die, means for moving the die parts together for the extrusion and apart to release the extruded 90 article, a container, an extrusion plunger, a slide for reciprocating said plunger, a fluid pressure cylinder and piston for reciprocating said slide, a traversing slide on said reciprocating slide and carrying said 95 plunger, and means for traversing said traversing slide across the machine, substantially as described.

100 21. In an extrusion press for the manufacture of tubes, rods, bars and the like, the combination of a divided die, means for moving the die parts together for the extrusion and apart to release the extruded article, an extrusion plunger, a slide for reciprocating said plunger, a fluid pressure 105 cylinder and piston for reciprocating said slide, and a dovetail connection between the head of the piston and said reciprocating slide, substantially as described.

110 22. In an extrusion press for the manufacture of tubes, rods, bars and the like, the combination of a divided die, means for moving the die parts together for the extrusion and apart to release the extruded article, an extrusion plunger, a pivotally mounted container adapted to be turned into and out of position coaxial with the plunger, and means for securing the container in said coaxial position, substantially 115 as described.

120 23. In an extrusion press for the manufacture of tubes, rods, bars and the like, the combination of a divided die, means for moving the die parts together for the extrusion and apart to release the extruded 125 article, an extrusion plunger, a reciprocating slide, a conical holder (38) trunnioned in said slide, and a conical container mounted in said holder, whereby the container can be turned into and out of posi- 130

tion coaxial with the plunger, and means for securing the container holder in the coaxial position, substantially as described.

24. In an extrusion press for the manufacture of tubes, rods, bars and the like, a longitudinally divided die in combination with power operated means for closing the die parts together.

25. In an extrusion press for the manufacture of tubes, rods, bars and the like, a longitudinally divided die in combination with power operated means for closing the die parts together and for moving the same apart.

15 26. In an extrusion press for the manufacture of tubes, rods, bars and the like, the

combination of half dies (20, 21) sliding members for closing and opening the half dies, half bolsters (26, 27) half rings (24, 25) fixed to the half bolsters and centering 20 and supporting the halves of the die, and half collars (26, 27) for securing the half bolsters to the said sliding members respectively and clamping the half dies to said half rings, substantially as described. 25

In witness whereof, I have hereunto signed my name in the presence of two subscribing witnesses.

LOUIS GEORGES DERAIN.
